UNITED STATES PATENT OFFICE.

WILLIAM W. BONSON, OF DUBUQUE, IOWA.

ATTACHMENT FOR DRY ORE-SEPARATORS.

1,214,269.

Specification of Letters Patent. Patented Jan. 30, 1917.

Application filed May 5, 1911, Serial No. 625,344. Renewed July 8, 1916. Serial No. 108,246.

To all whom it may concern:

Be it known that I, WILLIAM W. BONSON, citizen of the United States, residing at Dubuque, in the county of Dubuque and State of Iowa, have invented certain new and useful Improvements in Attachments for Dry Ore-Separators, of which the following is a specification.

Great difficulty has been experienced in the separation or concentration of ore arising from the fact that the mass to be separated from different mines and also in the same mine contains widely different percentages of values requiring different means for making the separation or different manipulation of devices for that purpose.

The object of my invention is to provide an attachment to the dry ore separator patented by me on the 3rd day of January 1911 and numbered 980,891; and it consists substantially in a table having a mesh and divided into two parts, on one of which parts the mass to be separated is received, and from the other side the separated ore is taken. It further consists in providing the whole table with ore riffles set diagonally to the movement of the table and in placing on these ore riffles, over the receiving side of the table, adjustable gangue deflectors set at an angle to the ore riffles, and in means for adjusting the gangue deflectors.

In the following specification, taken with the drawings, will be fully described the manner of constructing the device, together with the mode of operation whereby the objects sought may be accomplished.

Figure 1 is a perspective view of the table. Fig. 2 is a side view of an adjustable gangue deflector and a cross section of a number of the ore riffles. Fig. 3 is a vertical section on a line $\alpha-\alpha$ of Fig. 2. Fig. 4 is a perspective view, enlarged of the adjustable gangue deflectors and ore riffles and mode of making the adjustment.

As the construction of the table together with the manner of supplying air for the separation and the means by which the table is reciprocated may be the same as in the before mentioned patent, and since they form no part of my present invention they are not described herein.

Referring to the drawings, 2 designates the table and 4 the mesh upon the table. Upon this mesh are placed at short distances apart ore riffles 5 (shown in these drawings as set at an angle to the table) providing

runways between the riffles. Upon the top of the ore riffles are placed the gangue deflectors 6 each of which consists of a bar 7 and plate 8. The bar 7 extends across the 60 riffles 5 at an angle thereto and rests thereon. The plate 8 is provided with grooves or recesses 10 of the size of the riffles 5 and is adapted to be adjusted down to or nearly to the mesh on the table and placed parallel 65 and in contact with the bars 7. In order to adjust this plate substantially in a vertical manner it is supplied with an opening 12 in which one end of a spring 14 is adapted to engage, the other end of said spring is rigidly fastened to the bar 7 on the opposite side.

The manner of operating this device is substantially as follows: Power is applied to the table and the air is turned on against the under side of the table and passes up through the mesh and the mass is delivered upon the upper end of the table. The reciprocating motion of the table with the current of air up through, will immediately 75 stratify the mass and deliver the ore in the runways 15 between the ore riffles 5 and the gangue above the ore and between the gangue deflectors 6, then the operator watches the mass and estimates about the percentage of 80 ore that there is in the mass and if it is ore of great values, he leaves the plate 8 just level with the top of the ore riffles 5 but if it be of a small percentage then he takes hold of the spring 14 and forces down 85 the plate 8 with the ore riffles 5 in the recesses 10 near the mesh on the table and if the ore increases in values he raises the plate 8 in the same manner. It will be seen that the plate 8 is raised or lowered just as the 90 values increase or diminish, always permitting all of the ore to pass along under the plate 8 and the gangue over the riffles 5 and over the ore to one side of the table and very little will pass under the plates 8. It 95 will also be seen that when there is a small percentage of the values in the mass and the plates 8 are adjusted down close to or nearly to the mesh, that only a small amount of the gangue will be carried along 100 in the runways 15.

Having now described my invention what I claim and desire to secure by Letters Patent is:—

1. In a dry ore separator, a divided table 110 having a receiving side and a delivery side, a mesh upon the table, ore riffles on the mesh,

adjustable gangue deflectors set upon the ore riffles at an angle thereto on the receiving side of the table, and means for adjusting the gangue deflectors relative to the 5 mesh on the table.

2. In a dry ore separator, a table, a mesh on the table, ore riffles set on the mesh, gangue deflectors set on the ore riffles and each consisting of a bar secured upon the 10 ore riffles and a plate, said plate provided with recesses in one edge, and means for adjusting said plate relative to the surface of the table.

3. In a dry ore separator, a table, ore 15 riffles upon the table, gangue deflectors each formed of a bar and a plate set parallel to each other upon the ore riffles, and said plate provided with recesses in which the ore riffles engage, and means including a clasp 20 engaging the bar, and plate for adjusting the

gangue deflectors with the ore riffles in said recesses.

4. In a dry ore separator, a table, a mesh upon the table, ore riffles on the mesh set a short distance apart and providing runways 25 between the riffles, gangue deflectors provided with recesses therein and set upon the ore riffles and across said runways and adapted to be engaged by the ore riffles in said recesses, and means engaging the 30 gangue deflectors for adjusting said deflectors relative to the surface of the table to control the travel of the mass in the runways.

In testimony whereof I affix my signature 35 in presence of two witnesses.

WILLIAM W. BONSON.
